UNITED STATES PATENT OFFICE.

OTTO HERMANN HARTMANN AND EDUARD BLEITNER, OF KASSEL-WILHELMSHOHE, GERMANY, ASSIGNOR TO SCHMIDT'SCHE HEISSDAMPF-GESELLSCHAFT M. B. H., OF KASSEL-WILHELMSHOHE, GERMANY, A CORPORATION OF GERMANY.

STEAM BOILER.

Application filed June 15, 1923, Serial No. 645,500, and in Germany June 28, 1922.

- Our invention relates to steam boilers, and has for its object to safeguard the water and steam containers of such boilers against the injurious effects of uneven heating. 5 These containers are usually heated from one side, and this impairs the durability of the material from which the boiler is made. The heating with furnace gases produces local accumulations of heat in the boiler walls, 10 and this in time causes the material to weaken and also affects injuriously the riveted joints of the walls of said containers. This is the case especially when the boilers are made with upright tubes and are intended for high steam pressures. In boilers 15 of this type, the heat generally is applied particularly to those portions of the containers which have been weakened by their connection with the said tubes, and where 20 to compensate for such weakening the container walls are made of increased thickness. It has been proposed to protect those portions of the container walls which are exposed to the furnace gases by means of 25 asbestos plates or of partitions. This, however, decreases the effective heating surface. Furthermore partitions are liable to become incandescent under strong heating and in 30 that case they will be destroyed in time. The above-mentioned drawbacks are avoided by our present invention. For this purpose we arrange in advance of the water and steam containers, that is to say, on the 35 side of those containers which faces the source of heat, a wall made of hollow bodies, for instance, tubes containing a cooling medium. These tubes may be filled, for instance, with water, or a cooling medium such as steam or air may circulate through 40 them. In the former case the water passed through the tubes may be the boiler feed water, the apparatus then constituting at the same time a feed water heater or the tubes containing water may be used for the 45 generation of steam. In the latter case the tubes may act as a superheater structure for the steam or as a preheater for the air employed for supporting combustion in the furnace. The cooled wall formed in this 50 manner resists the destructive effect of the heat and forms a reliable protection for the container wall against the furnace gases. At the same time the heat absorbed by this protective wall is utilized in an advantageous manner. 55
- In the accompanying drawing, two forms of this invention have been illustrated as examples in connection with upright tube boilers. Fig. 1 is a cross section of a portion of a boiler embodying our invention; 60 Fig. 2 is a partial longitudinal section and Fig. 3 is a partial plan view; Figs. 4, 5 and 6 show a second form of this invention and corresponds to Figs. 1, 2 and 3, respectively. 65
- In the example of our invention illustrated by Figs. 1, 2 and 3, *a* indicates a steam and water collector forming part of the boiler. Tubes *b* extend downwardly from the lower portion of said collector or container in the manner well known in this type 70 of boiler. According to our invention a protective wall is placed at a suitable distance below the said container *a*, this protective wall consisting of tubes *c* extending lengthwise of the container and located between the adjacent upright tubes *b*. These tubes *c* are provided with lateral flanges or ribs *d* recessed as shown in Fig. 3 to fit around the adjacent upright tubes *b*. The flanges *d* of adjoining tubes *c* are in contact 75 with each other; they may simply abut against each other as indicated in Figs. 1 and 3 or, if desired, such flanges may overlap. We thus form a continuous wall consisting of the tubes *c* and their flanges *d* 80 which protects the container *a* and particularly the lower portion thereof from the injurious excessive heating action of the furnace gases. The wall constituted by these tubes *c* is supported at its ends upon the 85 boiler setting in any suitable manner. A cooling medium such as water, air or steam, may be circulated through the pipes *c*; if this cooling medium is water, it may be either the feed water on its way to the boiler, or 90 water to be converted into steam within the tubes *c*; if air is circulated through the tubes *c* such air may be employed to support combustion in the boiler furnace; if steam is circulated through the tubes *c* such steam 95 may be superheated by the action of the furnace gases, that is to say, in this case the tubes *c* would constitute a superheater for the steam. 100

In the second example of our invention 105 illustrated by Figs. 4, 5 and 6, the protective

wall located under the container *a* is formed by two sets of tubes *e* and *f*, of which the tubes *f* are arranged lengthwise of the container axis while the tubes *e* are arranged 5 at right angles to the tubes *f*. The tubes *e* are shown curved corresponding to the relative arrangement of the several tubes *f*; while this arrangement is preferred, we do not desire to restrict ourselves thereto. In 10 this form of our invention we generally use the upper transverse tubes *e* for the circulation of steam so that they will form a steam superheater, while the lower set of tubes *f* is generally employed as a feed water heater. 15 It will be seen that the two sets of tubes *e*, *f*, arranged crosswise of each other will form a practically continuous protective wall beneath the container *a*. Fig. 6 shows that the only openings in this protecting wall will 20 be very small and these small openings will, in the operation of the boiler, very soon be stopped by cinders, ashes and the like coming from the furnace so that the wall will then be absolutely imperforate. If it is not desired to rely on the closing of these openings 25 by the operation of the furnace, we might apply a filling of refractory material to close the small openings. The water tubes *f* and the superheater tubes *e*, are supported on the 30 boiler setting in such a way that after lifting these tubes from their supports, such tubes may be pulled out from between the upright tubes *b*. The superheater tubes *e* may be constructed in such a manner (see 35 Figs. 5 and 6) as to have two runs side by side between adjoining sets of upright tubes *b* and the two runs are connected at their ends by elbows or by chambered heads of appropriate construction. When the sets of

tubes *f* are so close to each other that there 40 is no room for placing two tubes *e* side by side between them, the two tubes *e* or the two runs could be located one above the other and we might also employ more than two runs of such tubes. 45

Various changes in the specific form shown and described may be made within the scope of the claims without departing from the spirit of our invention. 50

We claim:

1. In a steam boiler, a water container, spaced water tubes extending from said container and communication therewith, spaced protective tubes extending between and transversely of said water tubes, and means 55 for closing the gaps between said tubes.
2. In a steam boiler, an elongated water container, spaced water tubes extending from said container transversely thereof and communicating therewith, protective tubes 60 extending lengthwise of the container between said water tubes, and means for closing the gaps between said tubes to form a protective wall.
3. In a steam boiler, a steam and water 65 container, spaced water tubes communicating with said container and extending therefrom, and a protective wall for maintaining said container out of direct contact with the heating gases consisting of tubes 70 arranged lengthwise of the container between said water tubes and provided with flanges extending into mutual contact.

In testimony whereof we have hereunto set our hands.

OTTO HERMANN HARTMANN. [L. S.]
EDUARD BLEITNER. [L. S.]
